COMBINED CANNULA AND VALVE UNIT FOR BLOOD TRANSFUSION

Courtland H. Barr, Sr., Courtland H. Barr, Jr., and John W. Barr, Los Angeles, Calif.

Application December 27, 1955, Serial No. 39,500

Term of patent 14 years

(Cl. D83—1)

FIG. 1.

FIG. 2.

FIG. 3.

FIG. 5.

FIG. 4.

Figure 1 is a side elevation of a combined cannula and valve unit for blood transfusion, embodying our new design.

Figure 2 is a front elevation thereof.

Figure 3 is a top plan view thereof.

Figure 4 is a bottom plan view thereof.

Figure 5 is a fragmentary side elevation thereof, with the flexible tube element removed for clarity of illustration.

We claim:

The ornamental design for a combined cannula and valve unit for blood transfusion, substantially as shown.
